UNITED STATES PATENT OFFICE.

JOHN A. BRILL, OF PHILADELPHIA, PENNSYLVANIA.

DESIGN FOR A SIDE FRAME FOR CAR-TRUCKS.

SPECIFICATION forming part of Design No. 26,407, dated December 15, 1896.

Application filed November 3, 1896. Serial No. 610,989. Term of patent 14 years.

To all whom it may concern:

Be it known that I, JOHN A. BRILL, a citizen of the United States, and a resident of Philadelphia, in the county of Philadelphia and State of Pennsylvania, have invented and produced a new and original Design for a Side Frame for Car-Trucks, of which the following is a specification.

My invention relates to a design for a side frame for a car-truck, and said invention consists in the configuration of the frame, substantially as hereinafter described and shown.

Reference is had to the accompanying drawings, forming part of this specification, in which—

Figure 1 is a plan view; Fig. 2, a side elevation; Fig. 3, an end elevation; Fig. 4, a sectional elevation on the line A B, Fig. 2.

At 1 are the yokes, comprising the side pieces 2 and 3, bottom piece 4, and top piece 5, the side pieces 2 3 being parallel and perpendicularly disposed and the top and bottom being likewise parallel and horizontally disposed. The side piece 3 is united to the top and bottom pieces 4 5 by rounded lugs 6, which form a bifurcation into which a lug 7 on the top piece 5 extends, and through the lug and bifurcation extends a bolt 8. The arms 2 3 are recessed on the inside, as shown in dotted lines, Figs. 1 and 2.

The central portion 9 of the side frame is a flat metal bar 10 of the cross-section shown in Fig. 4 and is increased in diameter as it approaches the inner arms or sides 2 of the yokes 1. Extending outwardly from the inside of said central portion are wall-like figures 11, united at the top and bottom with outwardly-extending webs 12 13, which extend in opposite directions from the walls 11

to the yokes 1 and merge therein, as shown 40 in Fig. 1, the central portions of the top and bottom webs 12 13 and the walls 11 forming a rectangular pocket or recess 14.

The intermediate portion of the frame is extended above the top web 12 to form a rib 45 15, which lies in the same plane as the bar 10 and extends over the top of the intermediate portion and the top pieces 5 of the yokes. The outer arms 3 of the yokes are provided with a like and outwardly-extending rib 16, 50 staggered in relation to the rib 15, and in the same plane a rib 17 is formed on the piece 4, which merges into the bar 10, as at 18. The forward end of the piece 4 of the yokes is provided with lugs 19, forming a bifurcation, 55 and the lower portion of the piece 3 has a lug 20 extending into said bifurcation.

It will be noticed by reference to Figs. 1 and 2 that the arms of the yokes extend outwardly from the vertical plane of the intermediate bar 10 of the frame on the outside, or that opposite the pocket 14.

Under the top portion of the yokes are circular caps 21, which depend outwardly from the upper portion of the yokes and downwardly into the space between the arms 2 3 of the yokes.

Having described my invention, I claim—

The design for a side frame for car-trucks, substantially as herein shown and described. 70

Signed at the city of New York, county of New York, and State of New York, this 17th day of October, 1896.

JOHN A. BRILL.
